UNITED STATES PATENT OFFICE

102,341

DESIGN FOR A SANDAL OR SIMILAR ARTICLE

Jacob Stein, New York, N. Y.

Application November 3, 1936, Serial No. 65,659

Term of patent 14 years

To all whom it may concern:

Be it known that I, Jacob Stein, a citizen of the United States, residing in the city, county, and State of New York, have invented a new, original, and ornamental Design for a Sandal or Similar Article, of which the following is a specification, reference being had to the accompanying drawing, forming a part thereof.

The figure is a perspective view of a sandal or similar article, showing my new design, both sides of which are identical.

The front part of the upper is open at its toe. The heel part or counter has the bottom portions

of its front separated edges connected to the insole, the remainder of the bottom edge of the counter being not connected to the sole.

The upper front corners of said heel part are provided with eyelets through which a lacing cord can be passed. The bottoms of the front edges of the heel part of the upper are permanently separated by the full width of the insole.

I claim:

The ornamental design for a sandal or similar article, substantially as shown and described.

JACOB STEIN.
